(57) **CLAIM**

The ornamental design for a cart, as shown and described.

DESCRIPTION

FIG. 1 shows a perspective view of my design for a cart according to the invention.

FIG. 2 shows a side view thereof, with the opposite side being identical.

FIG. 3 shows a front side view thereof with the rear side being identical.

FIG. 4 shows a top view thereof; and,

FIG. 5 shows a bottom view thereof.

The broken-line showing of wheels in FIGS. 1-5 is for illustration purposes only and forms no part of the claimed design.
